A. BRON

DEVICE FOR SINKING HOLES IN THE SOIL

Filed Oct. 24, 1921

Fig. 1.

Fig. 2.

Inventor:

Aite Bron

By Lawrence Haugue

Attorney

UNITED STATES PATENT OFFICE.

ALTE BRON, OF AMSTERDAM, NETHERLANDS.

DEVICE FOR SINKING HOLES IN THE SOIL.

Application filed October 24, 1921. Serial No. 510,164.

To all whom it may concern:

Be it known that I, ALTE BRON, architect, a subject of the Queen of the Netherlands, residing at Amsterdam, Weesperzijde 134, 5 Netherlands, have invented certain new and useful Improvements in Devices for Sinking Holes in the Soil, of which the following is a specification.

My invention relates to a device for sinking holes in the soil by the aid of the flushing process. It is already known to sink holes in the soil by means of tubes to the lower end of which pressure water is supplied. The pressure water loosens the ground 15 and brings it upward under pressure.

I have found that in practising this process in the first place only very few holes are obtained with an exactly cylindrical wall and secondly much time is wasted, as sinking 20 the holes by means of flushing in the way wherein it is generally executed, proceeds too slowly to be economical.

The side walls of the holes show more or less important deviations from the cylindrical shape and they are often not quite vertical, owing to which it is afterwards very difficult to drive piles of timber, concrete 25 or other material.

According to my invention these inconveniences are removed and completely sound and smooth cylindrical side walls are obtained. Moreover the process goes on much 30 more quickly.

According to the invention in the execution of the process a flushing tube is used being preferably at some distance from its under end surrounded by a ring provided with a downward pointed cutting edge.

The ground is loosened and raised and 40 at the same time the wall of the hole is smoothed cylindrically by means of the ring moving downwards with the flushing tube. Preferably this ring is formed of two pieces, so that it consists of two substantially crescent shaped parts or rings, which may be 45 connected to each other by fixing means as e. g. screw-bolts and at the same time clamp the flushing tube.

Moreover both rings may be provided 50 with a bow, the upper end of which fits to the flushing tube, while the two upper ends

may be connected to each other. In this way it is absolutely assured that during the working the ring ever maintains its position with regard to the flushing tube. 55

The accompanying drawing illustrates an example of a device according to the invention.

Fig. 1 is a longitudinal section and

Fig. 2 is a plan view of it. 60

1 is the flushing tube. At some distance above its lower end a ring in two parts is attached to it. This ring consists of two substantially crescent-shaped parts or rings 2 and 3. In the middle of each of the straight sides 4 a box- or ring-half 5 is formed. These rings 5 clamp the flushing tube 1, after the fixing or clamping bolts 6 having been screwed by means of nuts 7. Each ring-half 2 and 3 is further provided with a cutting edge 7' at the lower end and with a bow 8 at the upper end, these bows being disposed diametrically with regard to the clamping sides 4. These bows are both provided at the top with an annular part 9. These 75 parts 9 may be attached to each other with bolts and nuts 10 for the sake of clamping the flushing tube, so that there is no danger of the parts 2 and 3 altering their position with regard to the tube 1. 80

When flushing the holes the cutting edges cut in the ground and thus form a smooth, exactly cylindrical side wall of the desired section. The piles may be driven immediately thereupon without delay as no resistance is met with. The cutting of the soil by the cutting edges 7 promotes a quick transport of the loosened ground upwardly and increases the pressure of the flushing water. 85

Finally a device according to the invention is distinguished by cheapness and simpliciness of construction.

Its fitting to the flushing tube and its removing therefrom are very easy and simple. 90

Having now particularly described and ascertained the nature of my said invention, I declare that what I claim to be my invention is:

1. Apparatus for sinking holes in the soil 100 by means of the flushing process whereby cutting of the soil to the desired section of

the hole is accomplished in the direction of the sinking, comprising a flushing tube, and a ring provided with a downward pointed cutting edge fitted to the flushing tube preferably at some distance from the lower end of said tube, substantially as described.

2. Apparatus according to claim 1, in which the ring is formed of two substantially crescent shaped members which are connected to each other by suitable securing means, and

which members at the same time clamp the flushing tube, substantially as described.

3. Apparatus according to claim 2, in which both members are provided with a bow, the upper end of which fits the flushing tube, while both upper ends are connected to each other, substantially as described.

In testimony whereof, I affix my signature.

ALTE BRON.
